UNITED STATES PATENT OFFICE

JOSEPH W. HUSK AND ROBERT L. OLSON, OF TACOMA, WASHINGTON, ASSIGNEES TO SYRACUSE WASHING MACHINE CORPORATION, OF SYRACUSE, NEW YORK, A CORPORATION OF DELAWARE

RINSING DEVICE FOR WASHING MACHINES

Application filed January 24, 1927. Serial No. 162,961.

Our invention relates to washing machines for domestic or family use and especially to such machines as are power driven. More particularly, our invention relates to the whirling basket, of such a washing machine, in which the clothes may be packed when removed from the washing section of the machine, and especially to the means for passing clear rinsing water through the mass of clothes whereby they are freed of all soap, and soapy or dirty water.

The objects of our invention are, first, to provide a means of passing clear water through the mass of clothes; second, to ensure the even distribution and flow of this clear rinsing water through all parts of the mass of clothing; third, to cause the water to pass through the mass of clothing under hydraulic and centrifugal pressure, thereby preventing any portion of the clothing from stopping the flow of the water therethrough; fourth, to provide means for confining the flow of water to the height at which the clothes are packed, thereby preventing the waste of water; fifth, to provide means for supporting and centering the rinsing water supply pipe; and sixth, to provide a cheap and effective means, of extreme simplicity, for conducting the water to the central axis of rotation of the clothes.

We attain these and other objects by the devices, mechanisms, and arrangements illustrated in the accompanying drawings, in which—

Fig. 1 is a perspective view of a washing machine equipped with our improved rinsing device; Fig. 2 is a partial side elevation of the rinsing and drying portion of the machine, parts of the outer container and of the inner rotating basket being broken away to reveal the interior thereof, the far side of said parts being shown in blank in order to prevent confusion with the near side; Fig. 3 is a vertical section of the center of the upper portion of the apparatus; Fig. 4 is a similar view of the lower portion thereof; and Fig. 5 is a cross-section of the screen tube and rinsing water supply pipe.

Similar numerals of reference refer to similar parts throughout the several views.

50 The washing machine unit shown in Fig. 1

is composed of a washing section and a rinsing and drying section. The washing section comprises a tub 1, with suitable washing or agitating apparatus therein, adapted to receive the soiled clothes, hot water and soap and to remove or dissolve the dirt from the clothes. The batch of wet clothes are then removed from the tub 1 and placed in the annular basket 2 within the container 3 of the rinsing and drying section. The basket 2 is then rotated and the free suds removed therefrom under the centrifugal action developed therein, the said suds being pumped from the container 3, through the outlet pipe 4 by means of the pump 5. Then the rinsing water is injected horizontally in a forceful spray, or series of small streams, in the central axis of the annular mass of clothing and the force of the flow, together with the centrifugal force developed as soon as the water engages the rotating clothing, forces this rinsing water outward through the mass of clothes, carrying with it all dirty and soapy water.

The apparatus for pumping the water out of the container, for supporting and rotating the basket, and the driving motor are similar to those at present in use in such rotating drying baskets and will be described only as it differs from the present machines or in order to clearly describe the complete machine.

Referring now more particularly to Figs. 2-5, it will be seen that the cylindrical container 3, of the rinsing and drying section, is securely mounted on the washing machine frame and is stationary therein, and that it is provided with a cast cover 6, hinged to the frame at 7. The cover 6 has a circular flange 8 which fits snugly within the upper rim of the cylinder 3, thereby firmly attaching the center of the said cover 6 to the machine frame. The said center of the cover 6 is provided with an axial hole and with a pipe 9 fitted therein and extending into the cylinder. The cover 10, of the annular rotating basket 2, is revolvably mounted on the said axial pipe 9 by means of a suitable bearing 11. The cover 10 is also provided with a circular flange 12 fitting snugly in the upper rim of the said annular rotating basket 2, 100

thereby firmly supporting and guiding the upper end thereof as it rotates.

The lower end of the basket 2 is centrally supported on the driving nut 13 on which it rests and from which it may be freely lifted for removal from the container 3. The driving nut 13 is mounted on the upper end of the driving spindle 14. An inverted cup or apron 15 extends down from the nut 13 and forms an air bell above the lower end closure of the said cylindrical container 3. A suitable packing box 16 surrounds the spindle 14 and is positioned above the water line in the said air bell and has a bearing 17 below it. An adjustable bearing 18 is provided and engages the lower end of the spindle 14. A floating bevel gear 19 is mounted on the spindle 14 and meshes with a drive bevel gear 20 on the drive shaft 21. Thus the basket 2 is supported by the adjustable thrust bearing 18 and held by the two bearings 17 and 11, and is rotated by the gears 19 and 20.

The basket 2 comprises, in its preferred construction, a metallic cylinder with holes 22 punched therethrough, thus providing easy egress for the water from the mass of clothes packed therein.

In our improved basket we provide a central perforated screen tube 23, having relatively large holes 24 therein, said tube 23 being securely fastened in the center of the bottom closure of the said basket 2, and extending axially upward therefrom to the cover 10 of the said basket. A drain hole 25 (Fig. 4) allows any water, which may be left in the tube after use, to pass freely out therefrom and into the said basket. The screen tube 23 is made of strong, stiff, material and will therefore permit the clothing to be packed quite tightly in the annular space between it and the outer wall of the basket, without displacing it. A small guide cup 26 is secured in the center of the lower end of the tube 23 and is adapted to receive the end of the rinsing water supply pipe, as hereinafter described.

The rinsing water for the machine is received under pressure from a faucet 27, connected to any suitable water supply, and is conducted to the machine by means of a suitable flexible hose 28 connected to a bent pipe 29, whose lower end is conical and is adapted to fit fairly tightly in the axial hole and pipe 9, of the cover 6. A long supply pipe or nozzle 30 extends from the end of the bent pipe 29 downward in the center of the screen tube 23 and its end enters the guide cup 26, above described. This pipe 30 is closed at its lower end and is provided with a number of very small holes or outlets 31, extending practically its entire length, these holes being preferably arranged in two opposite rows, as shown. The pipe 30 does not rotate, nor does it come in contact with any rotating portion of the machine except that, if it is not

placed in an exactly axial position, its lower end may engage the guide cup 26. In case the clothing to be rinsed does not reach near the top of the basket 2, then we prefer to cut off a portion of the rinsing water by slipping a shield pipe 32 over the upper portion of the rinsing pipe 30 (Fig. 2) to close the upper outlets 31 therein, said pipe 32 fitting closely on the pipe 30.

Thus it will be seen that, when the batch of wet washed clothing is rotated by the rotating basket 2, in which it has been packed, the centrifugal force developed therein drives outward all the loose suds and dirty water, and the pump 5 removes this water from the outside of the said basket as quickly as it collects in the bottom of the container 3. Also that, as soon as the pipe 30 is inserted in the axial pipe 9 and the faucet 27 is opened, the water therefrom is forced out of the many small outlets 31 in a series of jets or streams of equal volume, from one end to the other of the said pipe 30. These jets are not rotating. The tube 23 is separated far enough from the pipe 30 to permit each stream to spread slightly before it reaches the said tube. This tube 23 is rotating and is full of large holes, therefore each stream or jet thoroughly wets the clothes in the entire annular ring opposite the level thereof, the said jets striking forcefully through the holes 24 as they pass. The water thus at once soaks into the wet rotating clothing and the continual supply of such water, under stream pressure, together with the centrifugal force applied thereto through the rotation acquired from the rotating clothing, immediately impels each particle thereof to pass outward through the whole mass of clothing, and carry with it all soapy and dirty water remaining therein. In practice this rinsing action is so rapid and complete that in two minutes time the whole mass has been thoroughly rinsed and the water flowing therefrom is clear and clean. This rinsing action is aided by the fact that the pump 5 keeps the container 3 clear of all accumulation of water therein, thus permitting the basket 2 to throw off the water from the clothing as quickly as it arrives at the holes 22 therein.

When the rinsing has been thus completed, the faucet 27 is closed and the pipe 30 removed from the machine, while the rotation of the basket 2 is continued until the mass of clothing has thrown off the excess water therein.

Having therefore described our invention, what we claim, and desire to secure by Letters Patent is:—

1. A rinsing device for washing machines, comprising a fixed container; a rotating basket having a perforated outer wall; an axial, perforated, tube secured to and rotating with said basket and extending from end to end thereof and leaving an annular space wherein

- the clothes to be rinsed may be packed; a water supply pipe, positioned axially within said tube, and closed at its lower end and provided with a plurality of lateral outlets, each 5 adapted to direct a jet of water on the inside of said rotating perforated tube, whereby the clothes packed outside of the tube are uniformly wetted through its perforations and the water therein is driven outward through 10 the mass of clothes by the continuous jets thrown thereon and by the centrifugal action developed therein; and means whereby selected ones of the series of lateral outlets may be closed.
- 15 2. A rinsing device for washing machines, comprising a fixed container; a rotating basket having a perforated outer wall; an axial, perforated, tube secured to and rotating with said basket and extending from end to end 20 thereof and leaving an annular space wherein the clothes to be rinsed may be packed; a water supply pipe, positioned axially within said tube, and closed at its lower end and provided with a plurality of lateral outlets, 25 each adapted to direct a jet of water on the inside of said rotating perforated tube, whereby the clothes packed outside of the tube are uniformly wetted through its perforations and the water therein is driven outward through 30 the mass of clothes by the continuous jets thrown thereon and by the centrifugal action developed therein; and a shield pipe adapted to close selected ones of the series of lateral outlets.
- 35 3. A rinsing device for washing machines, comprising a fixed container; a rotating basket; an axial, perforated, tube secured to and rotating with said basket and extending from end to end thereof and leaving an annular 40 space wherein the clothes to be rinsed may be packed; a water supply pipe, positioned axially within said tube, and closed at its lower end and provided with a plurality of lateral outlets, each adapted to direct a jet of water 45 on the inside of said rotating perforated tube, whereby the clothes packed outside of the tube are uniformly wetted through its perforations and the water therein is driven outward through the mass of clothes by the continuous jets thrown thereon and by the centrifugal action developed therein; and means 50 whereby selected ones of the series of lateral outlets may be closed.
4. A rinsing device for washing machines, 55 comprising a fixed container; a rotating basket; an axial, perforated, tube secured to and rotating with said basket and extending from end to end thereof and leaving an annular space wherein the clothes to be rinsed may be 60 packed; a water supply pipe, positioned axially within said tube, and closed at its lower end and provided with a plurality of lateral outlets, each adapted to direct a jet of water 65 on the inside of said rotating perforated tube, whereby the clothes packed outside of the 70 tube are uniformly wetted through its perforations and the water therein is driven outward through the mass of clothes by the continuous jets thrown thereon and by the centrifugal action developed therein; and a shield pipe adapted to close selected ones of the series of lateral outlets.
- 75 5. In a device of the class described, a container, a rotating basket within the container, a water supply pipe positioned in the basket and being closed at its lower end and provided with a plurality of lateral outlets, and means whereby selected ones of the series of lateral outlets may be closed.
- 80 6. In a device of the class described, a container, a rotating basket within the container, a water supply pipe positioned in the basket and being closed at its lower end and provided with a plurality of lateral outlets, and a shield pipe adapted to close selected 85 ones of the series of lateral outlets.
